UNITED STATES PATENT OFFICE.

ARTHUR TREVOR DAWSON AND GEORGE THOMAS BUCKHAM, OF WESTMINSTER,
LONDON, ENGLAND, ASSIGNEES TO VICKERS LIMITED, OF LONDON, ENGLAND.

LOCK MECHANISM OF BREECH-LOADING GUNS.

1,163,812.

Specification of Letters Patent. Patented Dec. 14, 1915.

Application filed July 31, 1914. Serial No. 854,247.

To all whom it may concern:

Be it known that we, Sir ARTHUR TREVOR DAWSON, knight, and GEORGE THOMAS BUCKHAM, both subjects of the King of Great Britain, residing at Vickers House, Broadway, Westminster, in the county of London, England, have invented certain new and useful Improvements in or Relating to the Lock Mechanism of Breech-Loading Guns, 10 of which the following is a specification.

This invention relates to lock mechanism of the kind in which the lock frame is capable of moving laterally in a box slide on the breech screw carrier and in which a re- 15 priming device is employed, the said device comprising a primer magazine or hopper and a bolt which is carried by the laterally movable lock frame and by the movements it receives from a cocking hand lever, operates to extract the used primer from its 20 chamber in the vent axial and insert a new one in its place from the magazine or hopper.

According to this invention the primer 25 magazine or hopper occupies a stationary position at one side of the vent axial and the lock frame has a mouth or opening formed in it above the forward portion of the bolt sleeve so that when the lock frame 30 is moved into its fully open position, and the used or defective primer has been extracted, the bolt sleeve will lie beneath the exit opening of the magazine or hopper from which a primer will fall through the 35 mouth or opening in the lock frame on to the top of the bolt sleeve, in which position the said primer will remain during the movement of the lock frame into its closed 40 position. Upon the lock frame reaching its closed position, the cocking hand lever may be actuated to withdraw the bolt whereupon the new primer will fall into the bolt-way in front of the bolt ready to be pushed into the primer chamber of the vent axial when 45 the bolt is returned to its forward position.

In order that the said invention may be clearly understood and readily carried into effect, we will describe the same more fully with reference to the accompanying drawings, in which:

Figures 1 and 2 are respectively a rear elevation and a plan showing a constructional form of our improvements. Figs. 3 and 4 are sections taken approximately on 55 the lines 1, 1 and 2, 2 of Fig. 1. Figs. 5, 6 and 7 are more or less diagrammatic sectional rear elevations showing respectively the lock frame closed with the bolt in its forward position, the lock frame open with the bolt still in the forward position, and 60 the lock frame again closed with the bolt in its retracted position.

A is the breech end of the gun and B a portion of the carrier shown in dotted lines, C is the box slide and D the laterally mov- 65 able lock frame provided with the aforesaid mouth or opening D'.

E represents the primer magazine or hopper, F the bolt employed for inserting the primers into the primer chamber of the vent axial, F' the bolt sleeve, and F² the cocking hand lever which operates through an arm F³ upon the bolt sleeve for unlocking and retracting the bolt and moving it to the forward and locked position to insert the 75 primer and leave the striker F⁴ cocked.

In the example shown, the hopper E is detachably mounted in an opening in the box slide and as is clearly seen in Figs. 5 to 7 it is provided with a vertical partition 80 E' which divides the hopper into two chambers. The hopper is retained in position by a spring pin E². When the parts are in the firing position as shown in Fig. 5, the mouth or opening D' in the lock frame D 85 is some distance to the left of the exit opening of the hopper E. After the gun has been fired (or in the event of a misfire) the lock frame is moved laterally to the right, and the opening D' then comes beneath the 90 exit opening of the hopper with the result that the lowermost primer in the left hand chamber of the hopper falls upon the bolt sleeve as shown in Fig. 6, after the used or defective primer has been ejected. The re- 95 turn movement of the lock frame to the closed position causes the primer immediately above that in the opening D' of the lock frame, to be forced back into the right hand chamber of the hopper, the upper sur- 100 face of the lock frame then closing the exit opening of the hopper. When the lock frame reaches its closed position the cocking hand lever F² is operated to unlock 105 and retract the bolt thereby allowing the primer that was resting upon the bolt sleeve to fall into the bolt-way in front of the bolt head. Displacement of the cocking hand lever in the reverse direction then moves the bolt forwardly and locks it to 110

Figures 1 and 2 are respectively a rear elevation and a plan showing a constructional form of our improvements. Figs. 3 and 4 are sections taken approximately on 55 the lines 1, 1 and 2, 2 of Fig. 1. Figs. 5, 6

the lock frame, at the same time inserting the new primer into its chamber and leaving the striker F⁴ in the cocked condition ready to be released to fire the gun when 5 desired. A projection may be provided on the carrier to prevent the cocking lever from being operated until the lock frame occupies its completely closed position.

The opening of the lock independently 10 of the movement of the breech actuating hand lever may be effected by a lanyard lever H which is formed with an arm h that engages between collars H' on the guide bolt H². Thus when the lanyard 15 lever H is pulled it withdraws the guide bolt H' and permits the lock to move. This movement of the lanyard lever H also causes an extension H³ thereon to engage with a shoulder or projection F⁵ on a casing forming part of the striker F⁴ (Fig. 4) and thus retract the said striker.

What we claim and desire to secure by Letters Patent of the United States is:—

1. In the lock mechanism of ordnance, 25 the combination with a stationary primer magazine, of a movable lock frame and a firing bolt carried by the lock frame, said lock frame having an opening for the reception of a primer from the magazine 30 during the opening movement of the lock frame.

2. In the lock mechanism of ordnance, the combination with a stationary magazine, of a movable lock frame, a firing bolt 35 and bolt sleeve carried by the lock frame, said lock frame having an opening above the forward portion of the bolt sleeve through which a primer from the magazine falls on to the top of the bolt sleeve during 40 the opening movement of the lock frame.

3. In the lock mechanism of ordnance, 45 the combination with a stationary primer magazine, of a laterally movable lock frame, and a firing bolt carried by the lock frame, said lock frame having an opening for the reception of a primer from the magazine

during the opening movement of the lock frame.

4. In the lock mechanism of ordnance, the combination with a stationary magazine, 50 of a laterally movable lock frame, a firing bolt and bolt sleeve carried by the lock frame, said lock frame having an opening above the forward portion of the bolt sleeve through which a primer from the magazine 55 falls on to the top of the bolt sleeve during the opening movement of the lock frame.

5. In the lock mechanism of ordnance, the combination with a stationary magazine, 60 of a movable lock frame, a firing bolt and bolt sleeve carried by the lock frame, said lock frame having an opening above the forward portion of the bolt sleeve through which a primer from the magazine falls on to the top of the bolt sleeve during the 65 opening movement of the lock frame, means for retracting the bolt when the lock frame reaches its closed position, the primer then falling in front of the bolt, and for moving the bolt forward to insert the primer into 70 its chamber.

6. In the lock mechanism of ordnance, the combination with a stationary magazine, 75 of a laterally movable lock frame, a firing bolt and bolt sleeve carried by the lock frame, said lock frame having an opening above the forward portion of the bolt sleeve through which a primer from the magazine falls on to the top of the bolt sleeve during the 80 opening movement of the lock frame, means for retracting the bolt when the lock frame reaches its closed position, the primer then falling in front of the bolt, and for moving the bolt forward to insert the primer into 85 its chamber.

In testimony whereof we affix our signatures in presence of two witnesses.

ARTHUR TREVOR DAWSON.
GEORGE THOMAS BUCKHAM.

Witnesses:

HENRY KING,
ALFRED PEAKS.
